UNITED STATES PATENT OFFICE.

GEORGE E. MARLATT, OF PASADENA, CALIFORNIA.

TYPOGRAPHICAL MACHINE.

1,366,578.

Specification of Letters Patent. Patented Jan. 25, 1921.

Application filed June 27, 1918. Serial No. 242,332.

To all whom it may concern:

Be it known that I, GEORGE E. MARLATT, a citizen of the United States, residing at Pasadena, in the county of Los Angeles and State of California, have invented certain new and useful Improvements in Typographical Machines, of which the following is a specification, reference being had therein to the accompanying drawings.

- 10 My invention relates to typographical machines, such as linotype machines of the general organization represented in Letters Patent No. 436,532, to O. Mergenthaler, wherein circulating matrices are released by 15 escapements from the magazine in the order in which their characters are to appear in print and then assembled in line, the composed line transferred to the face of the mold, the mold filled with molten metal to 20 form a slug or linotype against the matrices which produce the type characters thereon, and the matrices thereafter elevated and returned through distributing mechanism to the magazine from which they started. 25 More particularly, it relates to machines equipped with a plurality of magazines containing matrices of different font or face, any selected one of which may be brought into action at will.
- 30 In one class of such machines, (as for instance the U. S. patents, C. Muehleisen, 786,140, March 28, 1905, and H. A. Agricola, Jr. 789,646, of May 9, 1905,) the magazines are arranged in constant relation to the as- 35 sembler entrance having receiving throats leading thereto, and the matrix releasing escapements actuated by reeds which extend through the throats or across the lower ends of the magazines, thus requiring the 40 matrices to pass between the reeds in their travel from the magazines to the assembler entrance. This arrangement of the actuating reeds necessarily restricts the size or thickness of the matrices which can be used 45 in the machine, as the space between the adjoining reeds is limited and cannot be increased without altering the entire keyboard mechanism or the magazine construction. These and other disadvantages have ren- 50 dered the class of machines above mentioned impractical.

Attempts to overcome the above mentioned difficulties have been more or less unsuccessful chiefly in that they involve objectionable forms and complications of matrix escape-

ments and also the holding of the terminal matrix back a distance from the discharge ends of the magazine and in changing the angle or measurement of the discharge throat immediately adjoining the magazine 60 from that which practice has shown to be most desirable. Practice has shown that the best results are obtained if the matrices rest flush with the discharge end of the magazine and the usual angle of the discharge 65 throat developed in connection with the single-magazine type of linotype is maintained.

My present invention is intended to avoid the above objections and aims to provide a 70 construction wherein the matrices may be discharged from any one of the magazines into the assembler entrance without having to pass between the escapement actuating reeds, and thus to allow the use of matrices 75 of any size or thickness which the magazines themselves are capable of handling. To this end especially, I provide a series of actuating members movable across the inner or lower magazine into operative relation to the 80 escapements of that magazine or those of the upper or outer magazine at will, and to permit such movement of the actuating members, I form or arrange the parts so as to leave a space between the lower magazine 85 and the floor of the throat, bridging said space by means of a plate or switch which is shifted to open or closed position automatically according to the direction of movement of the actuating members. 90

An object of my invention is to provide a machine in which not only are the matrix releasing devices retractable and selectively registerable with relation to the magazines, but also, and in the same machine, to provide for the selective registration of any or a group of magazines with the principal or primary discharge throat.

In the accompanying drawings, I have shown my invention in preferred form and 100 by way of example and as applied to a machine of the class stated, but obviously many changes and variations may be made therein and in its mode of application which will still be comprised within its spirit. 105 Thus, it may be applied to other forms of typographical machines, such as typesetters, typecasters, and the like, which handle type or dies instead of matrices. Generally speaking, I desire it to be understood that I 110

do not limit myself to any specific form or embodiment, except in so far as such limitations are specified in the claims.

Referring to the drawings:

5 Figure 1 is an enlarged perspective view from the right hand side of the machine showing in series the mechanism for operating the escapements of inner and outer magazines, and means for selectively connecting 10 the escapements of either magazine with the key-rods, the outer magazine, in this view, being in operable relation with the key-rods;

Fig. 2 is an enlarged right-hand elevation of the mechanism shown in Fig. 1, the 15 relative positions of the several elements being the same as in Fig. 1;

Fig. 3 is a perspective of a portion of the escapement actuating mechanism shown in Fig. 1, in which certain features hereinafter 20 described are more clearly illustrated;

Fig. 4 is an elevation similar to Fig. 2 showing the outer magazine disassociated from its escapement actuating mechanism;

Fig. 5 is an elevation similar to Fig. 2, 25 showing both the inner and outer magazines disassociated from their respective escapement actuating mechanisms and in a non-operative position in order to permit the removal of the inner magazine from operative position, and the substitution of another magazine therefor;

Fig. 6 shows the application of this invention to a form of typographical machine in which the magazines are selectively movable with relation to the matrix delivery channels; and

Fig. 7 is a rear elevation of a portion of the matrix escapement system, applicable to Fig. 6.

40 The matrices are stored according to font in the superposed channeled magazines 1 and 124 in registration with the fixed receiving throats 115 of the raceway or assembler entrance, the latter and its throats being 45 divided by the customary partition plates 116 into channels through which the matrices pass to the composing stick or assembler as they are released from the magazine. After their composition in line, the matrices are 50 presented to the casting mechanism for the production of the slug and thereafter carried upward and delivered to a distributing mechanism and thence to the magazine from which they were withdrawn. The release 55 of the matrices from the magazines 1 and 124 is controlled by the escapements 95 thereon which are arranged in series with relation to the channels in the magazines. The escapements of both magazines are adapted 60 to be actuated by a common series of reeds or operating devices 120, which are controlled from the keyboard (Fig. 6) in the usual way. The parts so far described except as hereinafter pointed out are or may

be of any well-known or approved construction.

It is desirable that a change from one to the other of the magazines may be effected with a minimum of effort on the part of the operator and in the least possible period of 70 time. Means for effecting this change from one to the other of the magazines and for obtaining a supply of matrices therefrom in the assembling of a line, is disclosed in Figs. 1 to 7, inclusive; and will now be described 75 in detail.

The matrix escapement mechanism of both the inner and outer magazines as shown in Figs. 1, 2, 4 and 5, is substantially the same for both magazines, except that an intermediate series of verge members 110 is employed in connection with the outer magazines for receiving the thrust of the actuating rods 111 and thus transmitting movement to the escapement members 98. 80 The pawl ends (Fig. 2) of the escapement members 98 extend through the rear plate of the magazine and beneath the upper ears of each lowermost matrix and each of the matrix channels in the magazine is associated with an escapement set in the usual manner.

A secondary series of escapement members 112 which have the form of a comb-spring is provided, and the pawl ends 113 thereof operate through the magazine rear plate at a point between the upper and lower ears of the second matrix from the bottom of the channel and are held normally self-sustained in a non-obstructing relation to said 100 matrix. Another series of springs 114 of similar form but without the pawl ends, bear against and hold the verge pawls in extended position across the path of the lowermost matrices, and when the pawls 98 105 are actuated by the selecting units leading from the keyboard, the lowermost matrix is released and drops by gravity into the channel 115 between the vertical partition 116 and thence to the assembling elements 110 (not shown).

The action of the verge pawls 98 causes the outer springs 114 to force the pawl-ends of the escapement springs 112 inwardly, in order that they may prevent the dropping 115 of the matrix next above the one which has been released, and insure the co-operation of the two sets of pawls. The upper, clamped ends of the springs 112 and 114 are thinner than their lower ends and the bending thereof is principally confined to the curved portions 117 on the inner and 118 on the outer springs.

If for any reason a matrix should retain a position such as to cause one of its ears to 12 prevent the movement of the spring pawls 112, the lower, free ends of the outer springs 114 receive the stroke of the upper end of

the verge pawls 98, and are bent without actuating the pawl spring. In a similar manner, the springs 114 receive any over-stroke of the verge pawls 98 caused by an 5 over-stroke of any of the units leading from the keyboard.

The springs 114 exert a constant pressure on the verge pawls 98, but are limited in their outward movement by a clamping 10 plate 119, which extends downwardly over the cavities in the springs 114 formed by the curved portions 118.

An auxiliary series of keyrods 111 is provided for actuating the escapement mechanism 15 of the outer magazine 1, and these rods are adapted to be moved in or out of operative relation thereto by means of a handle 122, which is positioned conveniently to the operator. Another series of keyrods 20 123 is associated with the escapement mechanism of the inner magazine 124, and the arrangement of the handle 122 and its connection with the two series of keyrods is such that the movement thereof for placing 25 one of the series of rods 111 and 123 in operative relation with its respective magazine escapement mechanism will automatically and simultaneously move the outer set of rods from operative relation with its escape- 30 ment mechanism.

The keyrods 111 which are associated with the outer magazine 1 are supported in a spaced relation to each other corresponding to the relative units of the outer magazine 35 escapement mechanism by means of suitable perforations or notches 25 (Figs. 2 and 6) in the channel plate 125 opposite the discharge end of the inner magazine 124, and the rods are movable in and extend through 40 the said perforations. A shield 126 extends across the top of the channel 115 and aligns with the bottom of the matrix channels of the inner magazine when said magazine is to be used, but when the outer magazine is 45 to be used, this shield is retracted, leaving a gap or space between it and the inner magazine, through which gap the actuating rods 111 pass to operative position in relation to the outer magazine. In position, angle and 50 size, the top surface of the shield may correspond to the established position, angle and size of the usual discharge throat at this point. This shield covers the series of notches through which the rods 111 move 55 when the rods are in inoperative position with relation to the outer magazine, and provides a smooth floor for the passage of the matrices from the inner magazine 124. The shield is carried by a pair or more of 60 arms 127 arranged at opposite ends and intermediate thereof, and the arms are rigidly held on a longitudinally disposed rock-shaft 128 on the rear of the channel plate 125, and have furcations 129 formed on their upper 65 ends which extend through suitable openings

in the shield 126 for effecting the movement of the shield.

The handle 122 is mounted on a disk 132, which is pivoted on a longitudinally disposed rock-shaft 133. The disk 132 has a 70 radially formed slot 134 adapted to receive and permit the movement therein of a pin 135 carried by a tubular arm 136, which telescopes and slidably receives a rod 137. A spring 138 is carried by the rod 137, and is 75 adapted to compress between the end of the arm 136 and a pin 139 secured in the rod for the purpose of holding the rod extended from the arm to the extreme of its movement. 80

The initial downward movement of the handle 122 for raising the keyrods into operative position releases the arms 127, and permits their movement by means of the springs 130, which are attached at one end 85 to the furcations 129 of the arms and at the outer end of the channel plate 125 by means of the screw 131, thus effecting the movement of the shield 126 forwardly, so that the keyrods 111 may pass thereby in their 90 upward movement.

The final movement of the handle 122 upwardly for the purpose of withdrawing the keyrods 111 from operative position moves the shield backwardly so as to cover 95 the series of perforations in the channel plate 125, through which the rods pass. A pin 140 in the upper end of the rod 137 engages and forces the arm backwardly against the tension of the spring 130; the pin moves 100 140 in the slot 141 in the channel plate 125 and guides the upper end of the rod 137, and when the shield 126 is thus moved, the pin 140 rests against the end of the slot 141. Further upward movement for purposes 105 which will be presently described, causes an over-stroke of the tubular arm 136 against the tension of the spring 138, which is provided for the purpose of receiving the impact of the stroke in such an event. 110

The shield 126 has grooves 26 in its upper surface to receive the under edge of the partitions 116, and thus maintain the partitions in accurate alinement with relation to the channels in the magazine. Either or both of 115 the edges of the shield may also have grooves or notches 27 for a similar purpose as indicated in the several figures of drawings and more clearly brought out in Fig. 6.

The rods 111 are substantially parallel and 120 the lower ends thereof are guided in suitable slots or holes in the upper curved channel 143 of the frame 144, which is held at opposite ends on arms 145, the forward ends of the arms 145 being carried by the shaft 133. 125 A pin 147 in the disk 132 extends outwardly from one side of the disk to a point beneath and engages the inner end 146 of the arm 145, thus serving to determine the relative position of the frame 144 when the handle is 130

in its lowermost position, and the keyrods 111 are in operative position. A spring 148, secured at one end to the inner end 146 of the arm 145, and at the other end to the disk 132, serves to maintain the engagement of the end 146 of the arm 145 with the pin 147, as well as to insure the downward movement of the frame 144 when the handle is raised to withdraw the rods 111 from operative position.

The lower ends 149 of the rods 111 are flattened and rounded and are pivotally held in the open bearings 150 in the upper ends of the vertical extensions 151 on the bars 152.

15 The bars 152 are mounted at their inner or forward ends on the shaft 133, as shown in Fig. 3, and the rear ends of the bars engage and seat in notches 154 in the lower series of keyrods 120 which are associated

20 with both magazines.

When the handle 122 is raised, the bars 152 are moved downwardly by means of a horizontal extension 155 on the bottom of the frame 144, which engages notches 156 in the 25 lower portions of the extensions 151 on the bars 152. The downward movement of the series of bars is limited by means of a longitudinal rod 157, which is secured at opposite ends in the brackets 158, and extends beneath 30 the entire series of bars.

The brackets 158 are secured to suitable portions of the machine frame at their forward ends by means of screws 159, the rear ends are provided with flat-topped lugs 160, 35 and the forward ends have upward extensions 161 in which the ends of the shaft 133 are journaled. A radially formed rib 162 extends outwardly from the bracket extension 161 and is provided with a plurality of 40 perforations 163, 164 and 165, which are adapted to receive the tapered end 166 of the handle stem 167 for holding the handle in various selected positions relative to its axis when it is raised or lowered for the purposes 45 set forth.

A flange 168 is formed on the inner end of the handle stem 167 and a spring 169 is carried by the stem between the flange and the end of the guiding sleeve 170 formed on the 50 disk 132, the spring serving to retain the inner end 166 of the stem 167 in the perforations 163, 164 and 165, as may be selected.

The handle 122 is slidably mounted on the disk 132 and it is necessary in order to change 55 the position of the handle, to move it outwardly from the disk 132 against the tension of the spring 169, such a movement withdrawing the tapered end of the stem from the perforations in the rib 162 preparatory 60 to placing the same in position for entrance into another of the perforations.

The disk 132 has an inwardly extending arm 171 which carries one end of a longitudinally disposed shaft 172 and the other 65 end of the shaft is carried by another similar

arm at the opposite side of the magazine. An arm 173 is secured to each end of the shaft with both ends extending from the shaft, and is pivotally connected at opposite ends with a link 174 by means of a screw 175, 70 and a shorter link 176 by means of a screw 177, respectively. The link 174 is pivoted at its forward end on a screw 178 to the handle 122 and the link 176 is pivoted at its inner end on a screw 180 to the forward end of an arm 179. The pivot screw 180 extends through an elongated slot 181 in the inner end of the disk arm 171 and the inner or rear end of the arm 179 is pivotally held on a longitudinally disposed shaft 182 80 at the rear of the series of keyrods 120, the ends of the shaft being supported on the flat-topped lugs 160 on the ends of the brackets 158.

The rear upper series of keyrods 123 which 85 are associated with the inner magazine 124 are slidably supported and guided near their upper and lower extremities in a frame 183, which is supported at two or more points on the shaft 182 by means of arms 184 suitably secured to the rear wall of the frame. Each of the rods 123 has a notch 185 formed in its forward edge which receives the edge of a flat bar 186 suitably held on the lower portion 187 of the frame 183, which limits the 95 downward position of the rods and retains them in the proper alignment in the frame.

The arms 179 and 184 are resiliently connected by means of a spring 188, which is secured at opposite ends to the pins 189 and 190 in the arms, and lugs 191 and 192 on the arm 184 and the hub 193 of the arm 179 are normally held in contact by the spring, this arrangement permitting the tilting of the frame 183 backwardly in order to afford access to the mechanism in front of the frame. 100

When the handle 122 is drawn forward to release the stem 167 from one of the perforations in the rib 162 for the purpose of lowering the series of keyrods 111, the centrally pivoted arm 173, the links 174 and 176, and the arm 179 operate to force the longitudinal frame member 194 backwardly and to thus disconnect the keyrods 120 from the extensions 153 from the bars 152. The upward movement of the handle then lowers the keyrods as previously described and the end of the stem 167 is permitted to rest in the central perforation 164 in the rib 162. As the handle is thus moved upwardly the 120 disk arm 171 moves downwardly, the arm 179 is moved therewith and the frame supporting member is deflected thereby sufficiently to place the upper keyrods 123 in operative relation with the inner magazine 124, 125 as shown in Fig. 4. A reverse movement of the handle reverses the relative position of the keyrods, and further movement of the handle until the end of the stem 167 registers with the perforation 165 causes an extreme 130

forward deflection of the keyrods 123 until their upper ends rest against the outer magazine keyrods 111 in front of the end of the magazine 124. The object of thus placing the keyrods is for the purpose, in a certain type of machine, of permitting the lowering and removal of the magazine 124 and the substitution therefor of another in operative position. The restoration of the keyrods to operative position is accomplished by means of a reverse movement of the handle.

The frame member 194 is supported at opposite ends on the arms 179 and is provided with slots 195 in the lower flat bottom to receive and through which the keyrods extend. The upper side of the frame is curved over in the direction of the keyrods 123, and is provided with slots 196 which register with the lower slots and which are adapted to slidably receive the upper keyrods 123. The upper and lower series of keyrods 123 and 120 are provided, respectively, with convex and concave ends between the upper and lower slots in the frame 194 for more effectively centering the rods one on the other.

In the event that the magazine 1 is designed to accommodate matrices of extreme thickness, it may be wider at the discharging end than the magazine 124 and the escapement mechanisms of both magazines being actuated by the common series of keyrods 120, it is necessary to off-set the keyrods 111 to an extent, which increases with each connecting bar 152, as the right hand edge of the magazine is approached. This is accomplished by off-setting the extension 151 of the bar 152 in one direction, and the inner or rear ends of the bars 152 in an opposite direction, as shown in Fig. 3. This view also shows very clearly the pivotal connection between the lower ends of the keyrods 111 and the extensions 151 of the bars 152.

In Fig. 6 is shown an adaptation of this invention to the magazine arrangement and escapement system disclosed in the recent U. S. Patent, No. 1,266,970, (Marlatt) and to similar arrangements. In said patent, the magazines are disposed one above the other in radial lines and are movable in unison to bring any two successive magazines in registration with two respective delivery channels, so that matrices may be withdrawn from either of the two magazines and mixed in the same line without moving the magazines.

With the exception of an optional arrangement in said Patent No. 1,266,970, the arrangement of parts and combination of features disclosed in Fig. 6 is believed to be distinctly new in so far as it provides not only for selectively registering any two of a group of magazines with the delivery channels, but also for selectively connecting the escapement operating members with the

selected magazines without placing a limit on the size of the matrices by obstructing their passage from either operative magazine, as would be the case with the objectionable arrangements mentioned in the preamble of this specification. This feature renders possible the mixing in a single line matrices from two magazines by utilizing both the primary and auxiliary delivery channels, but does not interfere with registering any one of the group of magazines with the primary delivery channel for rapid continuous assembling of the matrices. In this connection it should be understood that the magazines themselves are transposable in position, and interchangeable one with another, preferably by removing and inserting them edgewise in the manner disclosed in the above-mentioned Patent No. 1,266,970. Certain matrix-distributing features disclosed in said patent, and which need not be here pointed out, also render the substance of said patent particularly adaptable in connection with this present invention.

The form of matrix escapement shown in Fig. 6, is particularly well adapted, in connection with the operating and shifting mechanism heretofore described, for use in connection with magazines disposed one above the other in parallel or approximately parallel lines.

It is desirable, in order that the escapements may be readily connected and disconnected with and from the actuating rods 111 that the forward end of the verges 100 should aline with the ends of the magazine.

With this and other objects in view, I provide a series of duplex verges, each verge of the pair being separately pivoted to rods 2 and 3. The two verge members are adapted to act in unison for releasing the matrices from the magazine in the usual manner and the co-acting verges of each escapement are resiliently connected by means of a spring 4, which restores the verges to normal position after a matrix has been released. The springs are coiled about the wire from which they are formed, the straight portion of the wire extending through slots 5, (Fig. 7) in the rear end of the forward verge and terminating in a loop around the forward end of the rear verge. The inner ends of both verge members have pawls 6, which extend through slots in the bottom plates of the magazine and oscillate to release the matrices one at a time from the magazine. The operation of the forward verge 7 to release a matrix from the magazine also effects the operation of the rear verge 8, by means of the connection through the spring 4, the pawl 6 carried by the rear verge serving to prevent the passage of the second matrix. The spring restores the verges to normal position by alining, one against the other, the flattened over-

lapping portions of the two members and thus serving to re-align them with their pivot rods.

In the event of an overstroke of the keyrod 111, or in the event that a matrix retains a position preventing the action of the rear pawl, as frequently happens, then the front verge operates independently against the tension of the spring, permitting the forward matrix to be released. (See 2nd. magazine from bottom, Fig. 6).

For the purpose of this description the upper delivery channel 8 may be considered either fixed or movable. Arranged beneath it in series are pawls 9, held against the escapement levers 7 by the keyrods 111 when the keyrods are in their raised position. When the keyrods are lowered in manner similar to that heretofore described, the pawls 9 drop by turning on their pivot bar 10 to a position which permits the magazines to be moved past them, but not so far that the ends of the keyrods will not engage and raise them when required for use. Their downward travel may for this purpose be limited by a rib 11 on the rear wall of the upper channel 8. When the keyrods are lowered to operate the escapements of the lower magazine, their upper ends are moved back beneath the ends of the escapement levers by means of a guide plate 12 having perforations 20 close to its rear edge through which the keyrods pass. The guide plate is attached to the shield 126 by pins 13 passing through the channel plate 125 at intervals. These connecting pins may operate in the same notches through which certain of the keyrods pass. When the shield 126 is retracted or restored in the manner hereinbefore described, the guide plate 12 is moved therewith for registering the rods with the upper or lower escapements as described. The connecting levers 152 function in manner heretofore described, but the manner of connecting them with and disconnecting them from the keyrods 120 is somewhat different. A guide plate 14 is mounted on the brackets 158 by means of a fulcrum rod 15. A link member 16 connects an extension 17 of the guide plate with the operating handle 122, a pivot screw 20 joining a stem 19 of the handle to the connecting link 16 at a point close to the center on which the handle turns. When the handle is drawn forward to free it for moving the connecting levers 152, the guide plate 14 guides the keyrods 120 from beneath one or the other of contact knobs 18 on the levers 152. This permits the levers 152 to be moved and when so moved the restoration of the handle 122 automatically places the keyrods 120 in engagement with the selected knob on the connecting lever 152. The final upward movement of the handle moves the shield 126

to close the passageway for the rods 111, 65 and moves the guide plate 12 to engage the rods with the escapements of the lower magazine, as shown in dotted lines.

If it is desired to move the magazines, this is done before the rods are so connected, or 70 when the ends of the rods are at any point between the upper and lower escapements.

The description of the operation of this invention having been carried along in the body of the specifications, it is believed that 75 the operation will now be understood.

As previously stated, I have shown my invention only in preferred form and by way of example, and it will be obvious that many modifications and alterations therein and in 80 its mode of application will suggest themselves to those skilled in the art without departure from its scope.

Having thus described my invention, its construction and mode of operation, what I 85 claim and desire to secure by Letters Patent of the United States, is as follows:

1. In a typographical machine, the combination of inner and outer matrix magazines each having a series of escapements, a channelled raceway to receive the matrices therefrom and spaced from the inner magazine, a series of actuating members movable across or through said space into operative relation to the escapements of the outer or inner 90 magazine as desired, a shiftable intermediate element to bridge the space between the inner magazine and the raceway, handle actuated means for effecting the movement of the actuating members and for shifting the 95 intermediate element to active or inactive position according to their direction of movement, and means for locking the actuating handle in a selected position.

2. In a typographical machine, the combination of inner and outer matrix magazines each having a series of escapements, a raceway to receive the matrices therefrom, an intermediate element to conduct the matrices from the inner magazine to the raceway, and 100 an independently mounted series of actuating members movable across the inner magazine into operative relation to the escapements of the outer magazine at will, the said intermediate element being shiftable away 105 from the inner magazine clear of the actuating members when the latter are so moved.

3. In a typographical machine, the combination of inner and outer matrix magazines each having a series of escapements, a raceway to receive the matrices from the magazines, a shiftable intermediate element to conduct the matrices from the inner magazine to the raceway, a series of actuating members mounted independently of said 115 element, and movable across the lower end of the inner magazine into or out of operative relation to the escapements of the outer

- magazine, and means controlled by the movement of the actuating members, for shifting the intermediate element toward or from the inner magazine according to their direction of movement.
4. In a typographical machine, the combination of inner and outer matrix magazines each having a series of escapements, a raceway to receive the matrices from the magazines, a shiftable intermediate element to conduct the matrices from the inner magazine to the raceway, a series of actuating members mounted independently of said element and movable across the lower end of the inner magazine into or out of operative relation to the escapements of the outer magazine, handle actuated means for effecting the movement of the actuating members and for shifting the intermediate element to active or inactive position according to their direction of movement, and means for locking the actuating handle in a selected position.
5. In a typographical machine, the combination of inner and outer matrix magazines each having a series of escapements, a channeled raceway to receive the matrices from the magazines, a fixed channeled throat leading from the raceway to the inner magazine and formed so as to leave a space between it and the magazine, a series of actuating members arranged to be moved across or through said space into or out of operative relation to the escapements of the outer magazine, and a shiftable plate or switch to open or close the space between the inner magazine and throat according to the position of the actuating members.
6. In a typographical machine, the combination of inner and outer matrix magazines each having a series of escapements, a matrix receiving element arranged in operative relation to the inner magazine and one of said parts being shiftable away from the other to leave a space therebetween, and a series of actuating members adapted to be moved across or through said space into operative relation to the escapements of the outer magazine.
7. In a typographical machine, the combination of inner and outer matrix magazines each provided with a series of escapements, a raceway having a throat leading to the inner magazine and divided by partition plates into channels for the matrices, the said throat being cut away at its upper end to leave a space between it and the inner magazine, and a plate supported over said space and arranged to be slid toward and away from the magazine longitudinally thereof, the said plate being formed with cuts or notches in its edge to clear the partition plates during its sliding movements, and channels in its upper surface for positioning the partition plates.
8. In a typographical machine, the combination of inner and outer matrix magazines each having a series of escapements, rods to operate said escapements, a raceway to receive the matrices from the magazines, a fixed throat leading from the raceway to the inner magazine and cut away to leave a space between it and the magazine, a plate or switch bridging said space, and a guide plate carried by said plate and serving to place the escapement-operating rods in or out of engagement with the escapements of the lower magazine.
9. In a typographical machine, in combination, a group of matrix-magazines movable to selectively register with a primary and an auxiliary matrix-delivery channel, matrix escapements associated with said magazines, operating members for said escapements, and means for selectively connecting said escapement operating members with such magazines as are in registration with said matrix delivery channels and for withdrawing said escapement-operating members to a position out of engagement with either escapement system, and from in front of any operative magazine to permit the selective movement of the group of magazines.
10. In a typographical machine, in combination, matrix magazines, a matrix delivery throat leading therefrom, escapement actuating members insertible and retractable through said throat, a passageway for said actuating members, and a shield for closing and opening said passageway, said shield lying in the approximate plane of one of said magazines and serving as a passageway for the matrices from said magazine when said shield is in position to close the passageway for said escapement-actuating members.
11. In a typographical machine, in combination, matrix-magazines, a lower and an upper delivery throat for conveying the matrices from a lower and an upper magazine respectively, escapement actuating members insertible and retractable in front of said lower magazine, and an intermediate connection between the ends of said actuating members and the escapements of the upper magazine, said intermediate members being designed to be raised simultaneously and automatically with the raising of the actuating members and to drop to a position in front of and clearing the ends of the magazines when the actuating members are retracted.
12. In a typographical machine, a matrix-escapement verge having two pawl-carrying members and means for operating said members separately and in unison.
13. In a typographical machine, a matrix-escapement verge having front and rear verges, and means for operating the front

pawl thereof independently of the rear pawl.

14. In a typographical machine, a matrix escapement having two separable parts, each 5 part carrying a stop-and-release pawl, and a resilient connection by means of which one of said parts actuates the other part and also permits of independent operation of one of the parts.

10 15. In a typographical machine, a matrix escapement having two pawl-carrying members separately pivoted, the two members being held normally parallel with their pivot points by a resilient connection and

adapted to be separated one from the other 15 at the point at which they are so connected.

16. In a typographical machine, a matrix escapement formed of two separate and 20 separable pawl-carrying members, and a spring connection therebetween, said connection permitting the operation of one of said parts independently of the normal coacting part.

GEORGE E. MARLATT.
